TIME COMPUTING AND RECORDING
CLOCK

Browning Paton Wood, Montreal, Quebec, Canada

Application October 15, 1947, Serial No. 779,905

21 Claims. (Cl. 346—82)

1

This invention relates to improvements in time computing recorders and the primary object of the invention is to provide a time recorder having means for computing and recording the time elapsed between selected operations of the device. A further object is to provide a time computing recorder so constructed and arranged that it may be incorporated with, or have incorporated with it, many of the known varieties of instant time recorders. A still further object is to provide a time computing recorder which may be readily adjusted or modified to perform a variety of time computing and recording operations, according to the requirements of a variety of uses. Another object is to provide a device of the foregoing character which is simple, compact, inexpensive and rugged in construction. Still another object is to provide a time computing recorder adapted to automatically reset itself after making a record of computed time and to be thereafter inoperative until the commencement of the next time period of which a record is desired. Another object is to provide a time computing recorder adapted to continue its time computing, without resetting itself, after making a record of computed time, and to reset itself at predetermined times, or to become inoperative for time computing but without resetting itself. Still another object is to provide a time computing recorder responsive to the insertion of a record receiving element or to the operation of supervisory means, or to the operation of both such element and such means for the printing of records of computed time and for the starting and stopping of time computing operations. Various other objects and the advantages of the invention may be ascertained from the following description and the accompanying drawings.

Broadly stated, the invention consists in a plurality of computing and recording elements and integrating operating means therefor, together with means for automatically resetting the computing elements after a record has been made or for continuing the operation of the computing means after a record has been made, and means for rendering the computing means inoperative during periods of time when no computation of time is desired.

More particularly, the invention consists in the features and combinations of features herein disclosed, together with all such modifications thereof and substitutions of equivalents therefor as are within the scope of the appended claims.

The invention is susceptible of embodiment in a variety of ways, both as to the form and ar-

2

angement of the computing and recording elements and the resetting and operation controlling mechanisms therefor and as to the form and arrangement of the integrating operating mechanism therefor, and these may be used alone or in association with instant time recording mechanism of any suitable sort.

The most simple embodiment of the invention is one adapted to compute and record the working time of one man or one machine and to automatically reset itself after each recording of a computed work period. The invention also includes means whereby the operation of the time computing means and the resetting thereof are independent of the computation recording, and the computing mechanism is controlled by supervisory means for operation only at predetermined periods and for resetting at predetermined times.

The computing and recording elements may be of any suitable or desired form, such as of finite form arranged for reciprocation but are preferably of endless, unidirectional type, such as belts or wheels. Computing and recording elements of wheel form are now preferred and the following description will be confined to elements of this form and to integrating operating mechanism, resetting mechanism and operation controlling mechanism suitable thereto, but it will be understood the invention is not thereby limited to the wheel form of computing and recording elements or to the particular embodiments of the resetting mechanism, operation controlling mechanism or integrating operating mechanism hereafter described.

For simplicity of description and to facilitate understanding of the construction and operation of the invention, the elapsed time computing and recording elements will be hereinafter referred to as "computing wheels" and the instant time recording elements as "time wheels" and the same distinction will be applied to elements related thereto. The term "recording wheels" will be used as a generic or collective term denoting both the computing and time wheels.

According to my invention, rotatably mounted computing wheels having numerals in relief on the peripheral surfaces thereof for the printing of time computations are associated with an integrating operating mechanism to rotate the wheels in accordance with the passage of time; with means to suspend the operation of the computing wheels during desired periods of time and to render them operative during other periods of time and with means to automatically rotate the computing wheels immediately after

a recording of computed time has been made, or at any other predetermined time, to reset the wheels to "zero."

In the accompanying drawings, which illustrate those embodiments of my invention now preferred, but without limitation to the details thereof, and one form of associated instant time recording means, but without limitation to that particular type of instant time recording means:

Fig. 1 is a front elevation of an embodiment of the invention, the supervisory mechanism and the casing being omitted to show the primary resetting mechanism.

Fig. 2 is an elevation of the right hand side of the structure shown in Fig. 1.

Fig. 3 is a front elevation of the recording mechanism with parts removed to reveal the means for selectively rendering the computing mechanism operative or inoperative.

Fig. 4 is a rear elevation of the recording mechanism of Fig. 3.

Fig. 5 is an elevation of one of the computing wheels, showing the driving teeth thereof.

Fig. 6 is an elevation of the computing and recording mechanism, on an enlarged scale, looking in the direction of the arrow of Fig. 1.

Fig. 7 is an elevation of one of the computing wheels, on the scale of Fig. 6, showing parts of the resetting means.

Fig. 8 is a cross-sectional view of the computing wheel of Fig. 7, on the line 8-8 of that figure.

Fig. 9 is an elevation of one of the computing wheel resetting discs, on the scale of Fig. 6.

Fig. 10 is an elevation of the front of the computing rake lifting cam, on the scale of Fig. 6.

Fig. 11 is an elevation of the back of one of the computing rake cam driving discs, on the scale of Fig. 6.

Fig. 12 is a vertical sectional view of the recoil damping mechanism, on the line 12-12 of Fig. 2.

Fig. 13 is a diagram of one arrangement of the electrical circuits of the apparatus.

Figs. 14 and 15 are views similar to Fig. 3, showing, respectively, mechanical and electrical supervisory means to control the operation and resetting of the computing mechanism, omitted from Fig. 1.

Fig. 16 is a circuit diagram showing supervision of operating periods and resetting of the computing means.

Fig. 17 illustrates a fragment of a printed record of the type made by the apparatus.

Referring more particularly to the drawings, and first to those parts of the structure illustrated which are common to instant time recording and to elapsed time computing and recording and which may be of any suitable or well known construction, 21 designates a base and 22 the spaced main frame side plates fixed to the base and on which a time recording mechanism, designated as a whole by the numeral 23, is supported in any suitable way, as by a pin 24. The time recording mechanism 23 includes front, intermediate and rear frame plates 25, 26 and 27, respectively, rigidly connected together in spaced relation and lying in vertical planes transverse of the planes of the main frame plates 22. A shaft 28 is journaled in the lower parts of the front and rear frame plates 25 and 27 and carries the computing wheels 42, 43 and 44, hereafter described. An inverted U-shaped rake frame 29 is oscillatably mounted at the end portions of its arms on the shaft 28 and carries journaled therein a rake shaft 30, disposed parallel with the shaft 28. The rake shaft 30 carries a computing wheel rake 41,

hereafter described, for operating the computing wheels. A set of instant time recording wheels 31 may be mounted on the shaft 28 and an operating rake 32 for said wheels 31 may be mounted on the shaft 30. A motor 33, mounted in the main frame, drives a shaft 34 with cam 35 thereon at any suitable speed, preferably at one revolution per minute. The cam actuates a lever, link and spring mechanism 36, of any suitable sort, mounted on and between the plates 25 and 26 and connected to the rake frame to raise and lower the same at regular intervals of time, preferably once every minute, the frame being spring powered for return movement to shift the computing wheels and the time wheels, in the well known manner. Beneath the time recording mechanism 23, a vertically acting solenoid 37 carries a printing platen 38 upwardly thrustable against all the time recording wheels, whereby a time computation and an instant time record may be printed on a receiving element 39, such as a time card, inserted between the platen and wheels. When the element 39 is a time card, it may be used to initiate operation of the printing mechanism by inserting it far enough to rearwardly displace a trigger 40 actuating the circuit maker 41 (Fig. 13) of the solenoid 37, in the well known manner. Alternatively, the circuit of the solenoid may be closed by any other means at appropriate times.

It is to be understood that the mounting of the time wheels 31 on the same shaft 28 as the computing wheels and for operation by the same motor and in conjunction with the same printing mechanism as serves the computing wheels is purely a matter of convenience and that the shaft carrying the wheels 31 may be entirely separate from the shaft 28, either aligned therewith so as to locate the time wheels in close proximity to the computing wheels, so that instant time may be recorded beside the record of computed time, or the shaft carrying the wheels 31 may be located in any other desired position or place, with reference to the computing wheels. Likewise, while the time wheel rake 32 is illustrated as mounted on the same shaft 30 as the computing wheel rake, in conformity with the mounting of the wheels 31 on the shaft 28, it will be understood the rake 32 may be otherwise mounted, as on a separate shaft, to conform with the mounting of the time wheels.

Referring now to the mechanism peculiar to my invention; a series of computing wheels 42, 43 and 44 are rotatably mounted on the shaft 28. As illustrated in Fig. 6, the first computing wheel 42 is blank, that is, it does not bear numerals in relief on its peripheral surface. The second wheel 43 bears the numerals "0" and "1" to "9" in relief on its peripheral surface and the third wheel 44 bears the numbers "0" and "1" to "11" in relief on its peripheral surface. The foregoing arrangement of numerals provides recording computed time in hours and tenths of an hour, which computations are very convenient in subsequent use of the recorded computations, for example, in making up a pay roll. The computing wheels may, however, bear other series of numerals, and the number of wheels used may be more or less than the three wheels illustrated, according to the computation and record thereof desired, as will be well understood by those skilled in the art. For example, the blank wheel 42 may carry the numerals "0" and "1" to "9" on its peripheral surface and the wheel 43 may carry the numerals "0" and "1" to "5", in which case the computation and record thereof will be in hours and min-

utes. Likewise, the hour wheel 44 may carry numerals only from "0" to "9" and by the use of two or more of such wheels, the computation and record thereof may be extended to 99 or 999 hours, or more. Computations of this extent are sometimes required when the device is used to compute the running time of machines.

Each of the wheels 42, 43 and 44 is provided, at one side of the numeral row, with a circular series of ratchet teeth 45, the number of teeth corresponding to the number of numerals on the wheel. One tooth 46 on each of the wheels 42 and 43 is cut deeper than the others so that when the rake 47, hereafter described, engages this tooth it will be allowed to drop sufficiently to engage a tooth of the next wheel, to shift the same from one numeral to the next, as will be readily understood by all familiar with the construction and operation of counting mechanisms. For the mechanical convenience of limiting the amplitude of rake movement, it is preferred to form the wheel 42 with twelve teeth, of which two diametrically opposite teeth are deep teeth, as shown in Fig. 5, so that at each half revolution of the wheel, the rake may drop to engage the teeth of the wheel 43. This number of teeth corresponds to two series of numerals, each being "0" to "5" and each representing a six minute period. The opposite side of each of the wheels 42, 43 and 44 from the ratchet teeth is provided with an eccentrically disposed pin 48. Preferably, the pin bearing side of each wheel is annularly recessed, as at 49, and the pin is located in the recess and is sunk below the side surface of the wheel, as clearly shown in Figs. 7 and 8.

Resetting discs 50, 51 and 52 are associated with the computing wheels 42, 43 and 44, respectively. Each of these discs is irrevolvably mounted on the same shaft 28 as the computing wheels and each disc is substantially in contact with the recessed side of its associated wheel. The discs may be held in any suitable way against revolution on the shaft, but, preferably, by an integral spline 53 on each disc engaging in a key way or groove 54 formed lengthwise in the shaft 28. Each of the resetting discs carries, on the side thereof adjacent its associated computing wheel, a spring pawl 55 located and adapted to co-operate with the pin 48 of the computing wheel to drive the wheel for resetting and to allow the wheel to be rotated in a forward, or computing, direction. These pawls are preferably each formed of thin spring steel, riveted at one end to the disc and inclining away from it so that the free end of the pawl may engage the side of a pin 48 during the resetting movement of the disc to drive the wheel, and may yield to allow the pin to slide under it during the forward, or computing, movement of the wheel and during positioning of the disc for resetting purposes. By recessing the wheels in the manner described, the pins 48 and pawls 55 are contained in the thickness of the wheels, and the wheels and discs may be packed closely together for mutual support.

If desired, a single resetting disc may be associated with two computing wheels by using wheels recessed on adjacent sides and by providing spring pawls on both sides of the resetting disc, which is located between the wheels.

The rake 47 is of the type usual in counting mechanisms and is, in reality, a multiple pawl adapted to co-operate with the ratchet teeth of several wheels, selectively. The pawls, or teeth, of the rake are of different lengths, the longest being at the "units" end of the rake for engage-

ment with the teeth of the wheel 42 and the lengths of the pawls decreasing progressively toward the other end of the rake. During operation of the computing mechanism, the rake 47 is constantly in engagement with the ratchet teeth of the wheel 42 and is thereby normally held up out of contact with the teeth of the wheels 43 and 44. When, however, the wheel 42 has been rotated sufficiently to bring one of its deep teeth 46 in register with the rake tooth, the rake is allowed to drop sufficiently for its next tooth to engage a tooth of the wheel 43, to move the wheel the distance of one tooth, or numeral, thereof. Similarly, the rake is held up out of engagement with the teeth of the wheel 44 until a deep tooth of wheel 42 and the deep tooth of wheel 43 register and allow the rake to drop into engagement with the teeth of the wheel 44.

The rake 47 is irrevolvably mounted on the shaft 30 so that its engagement with the ratchet teeth of any of the wheels 42, 43 and 44 may be controlled. If the time wheel rake 32 is mounted on the shaft 30, it is revolvble thereon so that positioning of the shaft to control the computing rake 47 will not affect the operation of the time rake 32. Each of the computing wheels is provided with an associated spring pressed locking pawl 56 engaging the ratchet teeth 45 to hold the wheel against movement when the rake is slipping back over the teeth and when the pawl of the associated resetting disc is slipping over the pin 48. These locking pawls are mounted on a common shaft 57, which may also carry similar locking pawls for the time wheels.

The mechanism for resetting the computing wheels to "zero" after the recording of an elapsed time computation comprises, in addition to the resetting discs already described, a pinion 58 fixed to the front end of the shaft 28 and meshing with an intermediate gear 59 revolvably mounted on a stud 60 carried by the frame plate 25. The intermediate gear meshes with a quadrant gear 61 fixed to the end of a shaft 62 journalled in a bracket 63 carried by the plates 25 and 26. The rear end of the shaft has fixed thereto a pinion 64 meshing with a driving gear 65 fixed to a shaft 66 journalled in a bracket 67 carried by the right hand main frame plate 22. To ensure that the gear 59 does not overrun in resetting and that the shaft 28 and all elements driven thereby stop in exactly proper positions, the gear 59 carries a stop 59^a engageable with an abutment 59^b mounted on the frame. One end of a lever 68 is fixed to the shaft 66 and the other end is connected by an adjustable link 69 with the vertically movable plunger 70 of a solenoid 71 mounted in a yoke 72 on the main frame. The plunger is held against rotation by a steady head 73 running on pins 74 carried by the solenoid 71 mounting yoke 72. An adjustable stop is provided in any suitable place to limit upward movement of the plunger 70, for example, a screw 75 mounted on the main frame in the path of the steady head. A second lever 76 is fixed at one end to the shaft 66 and a tension spring 77 is connected between the free end of the lever and the base 21, to return the parts to original positions after each operation of the solenoid 71.

The spring 77 acts as a shock absorber to cushion the mechanism against shocks incident to the operation of the solenoid. To cushion the mechanism against shocks incident to operation of the spring, any suitable form of shock absorber may be used. One form which has been found very satisfactory is of the hydraulic type

illustrated and comprises an upright cylinder 18 pivoted at its lower end to a bracket 19 mounted on the base, and containing a piston 20 connected at its upper end to the lever 16. The lower end of the cylinder is connected by a passage 21 with a liquid reservoir 22, which may also communicate with the open top of the cylinder so as to receive any liquid leaking past the piston. A ball valve 23 is arranged in the passage 21 to permit free flow of liquid into the cylinder as the piston rises and to close against return flow of liquid while the piston is descending. A bleed passage 24 is provided leading from the lower end of the cylinder into the passage 21, to short circuit the valve 23. Flow through this bleed passage is controlled by a needle valve 25, at such rate that descent of the piston is retarded and the mechanism comes quietly to rest, without suffering any shock.

In order to render the computing wheels inoperative during time periods of which no computation is required, such as noon hour and at nights or during the time a machine is inoperative, means are provided for automatically lifting the computing rake 47 when the computing wheels have been reset to "zero" after the printing of computed time, and for automatically restoring the rake to operative position at the commencement of a time period which it is desired to compute. The mechanism for doing this comprises a disc 26 irrevolvably mounted on the front end of the shaft 28, preferably immediately behind the pinion 58; a pair of discs 27 and 28 revolvably mounted on the shaft 28 behind the disc 26; and means operated by the disc 28 to partially rotate the rake shaft 30. The disc 26 is formed with a notch 29 in its edge, the length of which notch is greater than the diameter of a pin 30 fixed to the second disc 27 and engaging in the notch. By this means, a lost motion driving connection is established between the disc 26 and the disc 27. The disc 27 is preferably larger in diameter than the disc 26 and carries a stop pin 31, beyond the perimeter of the disc 26, adapted to engage an adjustable stop 32 carried by the computing mechanism frame. The back of the intermediate disc 27 carries a pair of pins disposed 180° apart and each adapted to contact a spring pawl 33, similar to the pawls 55, mounted on the front of the disc 28. The pins and pawl constitute a one-way driving connection between the disc 27 and the disc 28. A spring pressed locking pawl 34 is mounted on the frame and engages the edge of the disc 28 to hold it against rotation during reverse rotation of the disc 27. The disc 28, which is really a cam, is formed with an abrupt drop 35. A lever 36 is pivoted on the frame plate 25 and has a downward projection overlying the cam 28. The free end of this lever engages under a roller 37 mounted on the free end of an arm 38 fixed to the front end of the rake shaft 30. At the opposite end of the rake shaft, an arm 39 is connected to a tension spring 40 mounted on the rake frame 29 and operating to hold the roller 37 down on the lever 36. A spring 41 mounted on the frame plate 25 engages the cam lever 36 and urges it against the cam 28.

If desired, means may be provided to indicate when the computing wheels are operating. One suitable means is a lever 42 pivoted intermediate its ends and interposed at one end between the cam lever 36 and its spring 41, and carrying at the opposite end, a signal 43 adapted to rise into a view opening 44 in the front of the casing

(not shown) when the computing wheels are operating.

As previously stated, when a time card is inserted between the recording wheels and the platen to printing position, it pushes back the trigger 45 to operate the circuit closing switch of the solenoid 31. The same switch closes the circuit of the solenoid 31. Since, however, the plunger of the solenoid 31 must drop immediately after a record is printed, while the operation of the solenoid 31 is retarded by the mechanism connected thereto, it is necessary to provide for different powering periods for the two solenoids. To this end, the circuit of solenoid 31 includes a pair of contacts 46 held closed by an arm 47 rigidly connected to the plunger 48 of the solenoid 31 as long as the plunger 48 is in its bottom position. As soon as the plunger 48 commences to rise, the arm 47 disengages the contacts 46, which open to break the circuit of the solenoid 31. The solenoid 31 has a holding circuit including a microswitch 49 controlled by a flexible actuator 50 pivoted on the base 21 adjacent the solenoid 31. One arm of the actuator is in contact with the switch and the other arm inclines into the path of a pin 51 carried by the plunger 48. As soon as the plunger commences to rise, the pin 51 engages the outer side of the actuator to rock the same on its pivot to operate the switch 49 and establish the holding circuit of the solenoid 31. When the plunger approaches the limit of its upward movement, the pin 51 passes the upper end of the actuator and releases the same so that the switch 49 is released and opens the holding circuit to de-energize the solenoid 31, allowing its plunger to drop. The pin 51 then travels down the inner side of the actuator until it disengages the same by passing the lower end 52 of it, which is flexed in the process and then returns to position for re-engagement of its outer surface by the pin at the next rise of the plunger.

For convenience of users of the device, a gear train 53 may be provided, powered by the shaft 34, to operate usual hour and minute hands sweeping a clock dial 54 which is visible through the view opening 44. It will be understood the mechanism is provided with means to feed an ink ribbon between the recording wheels and the platen, or with other suitable means for inking the printing characters on the wheels, but for simplicity of illustration such means has been omitted. Also, it will be understood that when necessary or desirable any known or suitable means may be incorporated to determine the position of a time card inserted under the printing wheels, thereby to prevent printing of one record upon a previous one.

As is usual with time clocks, the motor 33 operates continuously to rotate the shaft 34, preferably at one revolution per minute, so that once in each minute the mechanism 36 operates to lift the rake frame 29 and position the rakes for a fresh engagement with the ratchet teeth of the computing wheels and the time wheels. On completion of the upward movement, the return spring draws the frame down and any rake teeth which are in operative relation with recording wheel ratchets move the recording wheel or wheels forward a distance to register one minute of time. The forward movement of these wheels, with apparatus as shown in Figs. 1 to 3, is counterclockwise.

Assuming the parts of the mechanism are in the positions shown in Figs. 1 to 4, namely, with the cam lever 36 riding on the lift of the cam 28 and holding the computing rake 47 up in inopera-

tive position and that the computing wheels stand at "zero," the operation of the above described integrating operating mechanism has no effect on the computing wheels, which remain stationary. To start the device computing, a time card 39 is inserted in the space between the platen 38 and the recording wheels and actuates the trigger to close the circuits of the solenoids 37 and 71. The platen rises and drives the card against the recording wheels, thereby to print a record of the time registered by the wheels. The record of the computing wheels will be "0:0." If time wheels are associated with the computing wheels, the instant time, say, "8:00 A. M." will be printed beside the computed record.

When the solenoid 71 lifts its plunger, motion is transmitted through link 69, lever 68, shaft 66, gears 65 and 64, shaft 62, gears 61, 59 and 58 to rotate the shaft 28 in the backward direction of the computing wheels. Rotation of the shaft 28 causes rotation of the resetting discs 50, 51 and 52 in the backward direction of the wheels 42, 43 and 44. When the plunger finishes its stroke and the solenoid is de-energized, the spring 71 returns the parts to their former positions. The gear ratios in the above defined train and the adjusted length of the link 69 and the adjusted stroke of the plunger 70 are such that the rotation of the shaft 28 and the resetting discs thereon at each stroke of the plunger is slightly less than one complete revolution forward and the same amount backward, so that the pawls 55 of the discs do not quite pass the wheel pins 48 when the wheels are standing at "zero" and thus may return to former positions without moving the wheels.

Backward rotation of the shaft, as above described, rotates the notched driving disc 86 backward, or clockwise. It will be noted in Figs. 1 and 3 that the pin 90 on the disc 87 is at the left hand end of the notch 89 of the disc 86, this being its invariable position except when the rake control mechanism is in operation. The disc 86 thus rotates through the angle subtended by the notch, less the angle subtended by the pin 90, before the right hand end of the notch engages the pin 90 and imparts driving force to rotate the disc 87 backwards. During this backward rotation, one of the pins 93 on the back of the disc passes the spring pawl 94 on the cam disc 88.

On the downstroke of the plunger 70, the shaft 28 and disc 86 rotate in forward (counterclockwise) direction until the left hand end of the notch 89 again engages the pin 90 and movement is imparted to the disc 87 and from it, through one of the pins 93 and the spring pawl 94 to the cam disc 88 to rotate it forwardly and carry the cam drop 96 under the projection of the lever 97, so that the lever drops and releases the arm 99 of the rake shaft 30. The spring 101 then draws down the arm 100 of the rake shaft and thus rotates the shaft and draws the rake 47 fixed thereto down into operative relation with the ratchet teeth of the computing wheels 42, 43 and 44. The computing wheels are now operated, as already described, by the minute-by minute oscillation of the rake frame and rake under the power of the motor 33. This operation of the computing wheels continues until the next operation of the solenoids by the insertion of a time card, as already described.

At the next operation of the solenoids, say, at 12:06 P. M., the imprint made on the time card by the computing wheels will read "4:1," meaning that four-and-one-tenth hours have elapsed

since the record making at 8:00 o'clock. The time wheels will print the instant time record, namely, 12:06 P. M.

On the said second operation of the solenoids, the mechanism operates exactly as already described, excepting that on the rise of the plunger 70, the spring pawls 55 of the resetting discs 50, 51 and 52 will pass the pins 48 of such of the computing wheels as have moved, and that on the fall of the plunger, the pawls will engage the pins and move the computing wheels to reset them at "zero." Also, the second pin 93 on the disc 87 will engage the spring pawl 94 on the cam disc and rotate the disc one-half revolution to position the lift of the cam under lever 97, thereby to lift the lever to cause rotation of the rake shaft and lifting of the rake 47 out of operative relation with the computing wheels. Thus, while the clock continues to operate until the next record is printed, the computing mechanism remains idle.

While, in the foregoing description, the actuation of the mechanism has been described as being initiated by introduction of a time card and by movement of a trigger thereby to close the solenoid circuits, it will be understood the invention is not limited to this manner of use, as the actuation may be initiated by other means, such as by a push button control of the solenoid switch or by extending the solenoid circuit to be closed automatically, as by the starting and stopping of a machine to which the device is connected, the printed record being made on any suitable receiver therefor, such as a moving paper ribbon.

Since, in the operation already described, the resetting mechanism of the computing wheels functions at each operation of the solenoid 71 and since it is necessary that starting and stopping of time computation occur alternately, each at every second operation of the solenoid; the cam disc must turn only one-half revolution at each operation of the solenoid and this governs the amount of lost motion between the discs 86 and 87 and the number of pins 93 on the disc 87. For the timing of computation starting and stopping, as described, the amount of lost motion between the discs 86 and 87 need be only sufficient to ensure that only one of the pins 93 will pass the pawl 94 at each operation of the solenoid so that lowering of the rake is accomplished by a half revolution of the cam and raising of the rake by the next half revolution of the cam, and thus occur only on every second operation of the solenoid 71.

In other uses of the device, it may be necessary to provide for starting and stopping the computing wheels less often than at every second operation of the solenoid 71, for example, at every third or every fourth operation of the solenoid. This may be done by increasing the number of pins 93 to three, four or more and by correspondingly increasing the length of the notch 89 in the disc 86 so that the cam is rotated only one-third or one-fourth or smaller fraction of a revolution at each solenoid operation. By further increasing the number of pins 93 and the length of the notch 89, the rake lowering and the starting of the computing wheels can be arranged to occur only once in any desired number of solenoid operations. If the cam 88 is to be rotated less than one-quarter revolution at a time, it is desirable to increase the diameters of the discs 86 and 87, in proportion to the diameter of the cam, beyond that shown.

The invention is not limited to the form of driving connection between the solenoid and the shaft 28 which has been shown and described, as others may be used. One advantage of the form shown is that when it is necessary to remove the computing device from the main frame, all that is necessary is to withdraw the pin 24 and lift away the computing device. No connections between the computing device and the solenoid have to be taken down, as the gears 64 and 65 merely disengage. On assembling the computing device to the frame, after they are connected by the pin 24, it is a simple matter to mesh the gears 64 and 65.

To enable the time computing apparatus previously described to make successive records of a single time computation or successive records of different time computations without resetting after each recording, and to render the computing device operative and inoperative during predetermined periods of time, irrespective of computation recordings, as is necessary for recording computed time in respect of a number of men, supervisory means is provided. This means operates through controlling the raising and lowering of the computing rake 47 and may extend to controlling the operation of the solenoid 71. Suitable forms of apparatus are illustrated in Figs. 14, 15 and 16, but it will be understood the invention is not limited to the specific details thereof or to the association of the specific mechanisms of these figures with that of previous figures, as other forms of supervisory means may be used.

Referring to Figs. 14 to 16, 114 designates a twelve-hour wheel, that is, a wheel making exactly one revolution every twelve hours. This wheel may be a part of the clock train 112, such as the wheel driving the hour hand of the clock, or may be independent of the clock train and driven by any suitable means. A cam 115 is driven by the wheel 114, either directly or through intermediate means at the rate of one revolution every twelve hours, or every twenty-four hours, as may be desired. The face of the cam 115 is formed with notches or drops 116 of length and positioning according to the time periods at which it is desired to have the computing mechanism rendered inoperative. Each of the drops is abrupt at its leading end, being preferably radial of the cam, or even slightly undercut. As shown, the wheel 115 is a twelve-hour wheel and is formed with two drops 116 positioned to render the computing mechanism inoperative at, say, twelve o'clock and five o'clock, and hold it inoperative for, say, thirty to sixty minutes after each of these times. The cam lever 97 is provided with a tail 117 carrying a pin 118 extending laterally therefrom. A lever 119 is pivoted intermediate its ends on a bracket 120 carried by the frame plate 25. One arm of the lever 119 overlies the pin 118 and the other arm has pivoted to it a link 121 which carries a pin 122 riding on the face of the cam 115. The free end of the link 121 is supported in any suitable way, for example on the cam shaft. A tension spring 123 is connected between the lever 119 and the frame plate 25 to urge the pin 122 against the cam. This spring 123 is superior to the spring 102 which urges the lever 97 against the cam 88, so that when the pin 122 enters a drop of the cam 115, the spring 123 will overcome the spring 102 and lift the lever away from the cam 88, and also lift the rake 47 away from the computing wheels. The pin 122 is preferably cut diametri-

cally so as to provide a sharp edge and a flat surface facing the abrupt side of the cam drop, as shown, thus to enable the pin to fully enter the cam drop at a given instant, and not gradually.

In Fig. 15 there is shown an alternative mechanism designed for electrical operation. In this mechanism, the cam 115 is replaced by a disc 124 carrying electrical contacts 125 of any desired length in the circumferential direction of the disc, which contacts may be adjustable on the disc. The disc is electrically insulated from the rest of the mechanism and is fed with current through a slip ring and brush 126. A flexible contact arm 127 is positioned to be engaged by the contacts 125. The disc with its contacts and the contact arm are connected in series in the circuit of an electro-magnet 128, the armature of which, designated 129, is carried by the tail 117 of the lever 97. The disc 124, contacts 125 and contact arm 127 constitute a very simple form of "program device" to open and close a single circuit at times predetermined by the locations of the contacts 125 and to hold it closed for periods determined by the duration of engagement of the contacts with the arm 127. The mechanisms of Figs. 14 and 15 do not supervise the operation of the resetting solenoid. This supervision may be effected by any other suitable means, such as a pair of contacts in the powering circuit of the solenoid arranged to be operated by the clock train 112, or manually, or by a master clock. In Fig. 16 there is shown a diagram of circuits by which operations of the magnet 128 and of the solenoid 71 are controlled by a single program device 130 of any suitable or conventional construction in which the contacts are formed and arranged to close the circuits of the magnet and of the solenoid independently of one another at desired instants, hold them closed for predetermined periods of time and then open them.

In the operation of either of the mechanisms shown in Figs. 14 and 15, the powering circuit of the printing solenoid 37 is separated from the powering circuit of the resetting solenoid 71, so that record printing and the resetting of the computing mechanism will be entirely independent of one another.

For computing and recording an ordinary day's work for a number of men, the operation is as follows: At some time prior to 8:00 A. M., the computing wheels have been set at "zero" and the computing rake lifted so that if men insert their time cards before 8:00 A. M., the printed record, if time wheels are associated with the computing wheels, is actual time and "0:0" computed time. At exactly eight o'clock, the powering circuit of the solenoid 71 is closed, either manually or by a supervisory program device, and the solenoid operates the mechanism as already described to lower the rake 47 into operative position, so that records thereafter printed will show the actual time of printing and the computed time since eight o'clock. Since, in this application of the invention, the circuit of the printing solenoid 37 is separate from that of the resetting solenoid, as already stated, the printing operations do not affect the solenoid 71 and do not cause resetting of the computing wheels or lifting or release of the rake 47. Thus, any number of men may "punch in" during the period from shortly before eight o'clock until, with the wheels illustrated which compute by tenths of an hour, six minutes after eight o'clock and all will receive the same computed time record, namely "0:0." The printed instant time record

will show the number of minutes before or after eight o'clock. Any man punching in at six minutes after eight o'clock and up to twelve minutes after eight o'clock will get a record of, say, "8:08 A. M. 0:1." The computing mechanism remains in operation until twelve o'clock noon. If men punch out before noon, the printed record shows the fact, the exact time of the "punch out" and the computed time since eight o'clock. From eight o'clock until noon, the cam 115 holds up the pin 122 against the urge of the spring 123 and thereby so positions the link 121 and the lever 119 as to leave the pin 118 free, whereby the lever 97 will be held down by its spring 102 to release the rake for operation. At exactly noon, the cam 115 has rotated to position one of its drops 116 in register with the pin 122. The pin is drawn into the cam drop by the spring 123 and the link 121 and lever 119 are moved to depress the pin 118 and move the lever 97 to cause lifting of the rake 47 out of operative position so that the computing wheels cease to rotate and remain at the computed time of "4:0" hours. The records made by men "punching out" late is, therefore, "4:0." At about half past twelve o'clock, when all men have punched out, the computing wheels are reset to "zero" by operation of the solenoid 71 under manual or program device supervision, but the rake remains lifted out of operative relation with the computing wheels. At one o'clock, the solenoid 71 is operated, under control as before, to lower the rake 47 for operation of the computing wheels. Thus, men "punching in" shortly before one o'clock make a record of "0:0" hours and men "punching in" later than six minutes after one o'clock make a record showing the computed time lost. Between noon and about half past twelve o'clock, rotation of the cam 115 will have moved the drop 116 out of register with the pin 122, thereby moving the same outwardly to shift the connected mechanism and release the lever 97. In the afternoon hours, the operation is merely a repetition of that described for the morning hours. At five o'clock, the cam 115 releases the mechanism to lift the rake 47 and stop the computing wheels. At, say, half past five o'clock, the solenoid 71 is operated under supervision as before to cause resetting of the computing wheels to "zero" and to position the cam 88 to hold the rake up, the rake being at, or shortly after, this time freed from the urge of the spring 123, by the rotation of the cam 115. The mechanism is now set for operation at eight o'clock the next morning.

In the arrangement shown in Fig. 15, the contact disc 124 functions as the cam 115 and the magnet 128 as the spring 123. The lengths of the contacts 125 determine the time periods during which the magnet holds the rake up and are equivalent to the lengths of the cam drops 116. It will be obvious that the magnet 128 may be under control of the same program device 130 as supervises the solenoid 71, in which case the cam 115 with its attendant mechanism and the contact disc 124 will both be omitted.

If provision is to be made for computing hours of night work, the cam 115 is formed with the necessary additional drops or the disc 124 is provided with the necessary additional contacts.

The program device may be remote from the computing and recording mechanism and may supervise the operation of a number of such devices, or it may be closely associated with the computing mechanism, being in part the disc 124, which may then carry a second row of contacts.

to control the powering of the solenoid 71, so that the solenoid will be controlled primarily by the clock motion 112 and its operation perfectly synchronized with the operation of the magnet. 5 It will be obvious that, with a completely electrical supervision, the magnet 128 may be mounted directly on the rake frame 29 in position to act directly on the rake 47 to lift the same without intervention of the lever 97.

10 While, in the foregoing description, the elements 37 and 71 have been shown and described as "solenoids," for the reason these are a very satisfactory type of prime mover for their purpose, it will be understood that other types of prime movers may be provided and are to be regarded as mere mechanical equivalents of the solenoids for the purposes of this invention. For example, the solenoid 37 may be replaced by a conventional trip spring and cocking lever arrangement for manual operation and the solenoid 71 by a rotary electric motor or by a spring motor, either of which may be controlled by insertion of a time card or by supervisory means as already described, or even manually. Also, the solenoids may be replaced by pneumatically powered plungers under control substantially as already described.

15 20 25 30 35 40 45 50 55 60 65 70 75 It will be seen from all the foregoing that my invention provides means for computing and recording elapsed time under a considerable variety of conditions to meet the requirements of industry; for suspending the operation of the computing means while holding the computation during predetermined periods of time; for starting and stopping computation at predetermined times and for automatically resetting the computing means, either after each recording or at predetermined times.

Having thus described my invention, I claim:

1. In a time computing recorder comprising, time computing and recording elements; a continuously operating actuating means for said computing elements and driving connection between said actuating means and said elements, including pawl means to move said computing elements; means to move the computing elements for resetting the same and means operative at predetermined times to move said pawl means out of operative relation to the computing elements and after a predetermined number of operations of said resetting means into operative relation therewith.

2. In a time computing and recording apparatus comprising, time computing and recording elements; a continuously operating actuating means for said elements and driving means between said actuating means and said elements; means to position said driving means selectively in operative and in inoperative positions relatively to said elements; and means controlling said positioning means, including means to urge the positioning means to release the driving means for operative engagement with the elements; and a cam having a lift to hold said controlling means against said urge and in suchwise that the positioning means holds the element driving means in inoperative position, the last said means including a shaft on which the cam is rotatable; ratchet driving connection between said shaft and said cam; a prime mover operatively connected to the shaft to rotate the same alternately in reverse and in positive directions; and means to control said prime mover for operation at predetermined times.

3. In a time computing recorder comprising, a

rotatably mounted shaft; time computing and recording elements rotatably mounted on said shaft and driving means to rotate said elements on said shaft for time computing; resetting discs irrevolubly mounted on the shaft adjacent the elements; ratchet means for each said element to rotate the same in positive direction for resetting, comprising a pin on one of said element and its associated disc and a spring pawl on the other of said element and associated disc; and means to rotate said shaft in reverse direction to position said discs for element resetting and subsequently in positive direction for element resetting.

4. In a time computing recorder comprising, a rotatably mounted shaft; time computing and recording elements rotatably mounted on said shaft and pivotally mounted pawl means engageable with said elements to rotate same for time computing; means to position said pawl means selectively in operative and in inoperative relations to said elements, including a pawl position controlling lever; a cam rotatable on said shaft controlling the position of said lever; a cam driving disc rotatable on said shaft; ratchet driving connection between said disc and said cam; lost motion driving connection between said shaft and said disc; and means to rotate said shaft in positive and reverse directions.

5. In a time computing recorder comprising, a rotatably mounted shaft; time computing and recording elements rotatably mounted on said shaft; element driving means including a frame oscillatably mounted on the shaft and pawl means pivotally mounted in said frame; an arm connected to said pawl means to control operative engagement thereof with said elements; a lever engaged by said arm; said lever being formed in suchwise that the arm may reciprocate thereon during oscillation of the frame without altering the relative positions of the arm and frame; a cam controlling the position of said lever; and means to partially rotate said cam whereby the lever and arm are shifted to move the pawl means out of operative relation to said elements and to further partially rotate said cam whereby the lever and arm are shifted to move the pawl means into operative relation to said elements.

6. In a time computing recorder comprising, time computing elements; means to actuate said elements for time computing and means to print a record of time computation registered by said elements, including a prime mover; means to move said elements between computing periods for resetting thereof, including a prime mover, and means to render said elements inoperative at one resetting thereof and to hold them inoperative during at least one further resetting and to render them operative upon a predetermined number of resettings.

7. In combination with structure according to claim 6, means responsive to movement of a record receiving member into record receiving position between the elements and the printing means to initiate action of both said prime movers.

8. Structure according to claim 6 in which the prime movers are solenoids and in which controlling means therefor includes a circuit breaker for said first solenoid operating instantly on solenoid operation and a holding circuit for said second solenoid to prolong the powering thereof during a major portion of the stroke thereof.

9. In a time computing recorder comprising,

time computing elements and means to actuate said elements for time computing; means independent of said actuating means to move said elements for resetting including, a prime mover having a reciprocatable part; means controlling the powering of said prime mover including a pivoted member extending along a portion of the path of travel of said reciprocatable part and inclined to and crossing said path and adapted to be engaged by said part during movement thereof in one direction and moved thereby to maintain powering of said prime mover during said engagement, said pivoted member being adapted to position itself out of the path of movement of the reciprocatable part during movement operation of the first.

10. In a time computing recorder comprising, time computing elements and means to actuate said elements for time computing; means to actuate said elements for resetting including a solenoid; a primary powering circuit therefor including normally open contacts held closed by the solenoid plunger while at rest; a holding circuit for said solenoid including normally open contacts adapted to be closed at the commencement of powered plunger movement and held closed during a portion of such movement and thereafter to remain open to permit return of the plunger.

11. In a time computing recorder comprising, time computing elements and means actuating said elements for time computing; means to move said elements independently of the actuating means for resetting the same comprising, a solenoid; driving connection between said solenoid and said elements; a spring opposing the operation of the solenoid to cushion the driving connection against shock and to return the driving connection to original position; and a recoil damping means to cushion said driving connection against shock due to recoil action of said spring.

12. In a time computing recorder comprising, a rotatably mounted shaft; time computing elements rotatably mounted on said shaft and actuating means for said computing elements oscillatably mounted on said shaft including pawl means normally operatively engaging said elements; means to rotate said shaft in operating cycles each comprising approximately one revolution each in reverse and positive directions; resetting discs irrevolubly mounted on said shaft; ratchet driving connection between said discs and said elements for moving said elements in computing direction independently of the actuating means thereof, thereby to reset the elements; and means to control operative engagement of said pawl means and said elements, thereby to determine the duration of and intervals between time computing operations comprising, a cam rotatably mounted on said shaft; lever mechanism controlled by said cam to move said pawl means into and out of operative relation to said elements; and ratchet driving connection between said shaft and said cam adapted to move the cam in integrating manner, whereby the cam is rotated one complete revolution during, at the least, every two operative cycles of said shaft.

13. In combination with structure according to claim 12, powered timing means engaging said lever mechanism to hold the same and the connected pawl means in inoperative position independently of release by said cam for operation.

14. Structure according to claim 12 in which

the driving connection between the shaft and the cam comprises a disc fixed to said shaft; a disc rotatable on said shaft; lost motion driving connection between said discs; a pawl carried by one of said disc and said cam; and a plurality of teeth carried by the other of said disc and said cam, engageable successively by said pawl.

15. In a time computing recorder, including a shaft; revolvably mounted time computing wheels; means for driving said wheels for time computing comprising, a frame oscillatably mounted on said shaft and pawl means pivotally mounted on said frame and engageable with said wheels to drive the same in integrating manner; means to control engagement of said pawl means with the wheels for control of the duration of and the intervals between time computing operations comprising, a cam on said shaft; a lever riding on said cam; a lever connected to said pawl means and riding on said first lever, said second lever moving in an arcuate path by reason of the oscillation of the frame; said first lever being curved in the part thereof engaged by said second lever to conform approximately to the arcuate path of the second lever, whereby positioning of the pawl means by said cam is unaffected by oscillation of the frame; and means to rotate said cam through a fraction only of a revolution at each operation thereof.

16. In a time computing recorder, a rotatably mounted shaft; time computing and recording elements rotatably mounted on said shaft for time computing; resetting discs irrevolvably mounted on said shaft; ratchet driving connection between said discs and said elements; means to rotate said shaft in reverse and in positive directions, relatively to the movement of said elements in computing, to respectively position said discs for element resetting and to subsequently reset the elements.

17. Structure according to claim 16 in which the shaft rotation is limited to less than one revolution, whereby the ratchet driving connection of elements which have not moved does not operatively engage said elements and the elements remain stationary during resetting of elements which have moved.

18. In combination with structure according to claim 16, means to render said elements inoperative upon one reverse and positive rotation of said shaft and to maintain the elements inoperative during at least one succeeding reverse and positive rotation of said shaft, comprising a cam and a driving disc rotatable on said shaft; a pawl on one of said cam and disc; a plurality of teeth on the other of said cam and disc for engagement by said pawl; and a lost motion driving connection between said shaft and said disc adapted to move the disc through the angular distance between adjacent teeth thereof upon each reverse and positive rotation of said shaft.

19. In a time computing recorder, a main frame; a sub-frame; time computing elements mounted in said sub-frame; means for controlling the periods of operation of said elements and for

resetting the elements, mounted partly on said main frame and partly on said sub-frame and including a pair of interengaging members, one on the main frame and the other on the sub-frame, disengageable on separation of the main and sub-frames without altering the adjustment of either part of said means.

20. A time recording device comprising a shaft; a plurality of printing wheels rotatably mounted on said shaft; a continuously oscillating rake having pawls to operatively engage said printing wheels; means to move the pawls associated with certain of said wheels out of operative relation with the wheels and to hold them out of operation with the wheels while the rake continues to oscillate, whereby said certain wheels remain stationary and hold a record registered thereby while the other wheels continue to be operated; means to print a record from all said wheels; and means associated with said printing means for releasing the pawls of said certain wheels for operative engagement with the wheels after a predetermined number of operations of the printing means.
25. 21. A time recording device comprising a shaft; a plurality of printing wheels rotatably mounted on said shaft; a continuously oscillating rake having pawls to operatively engage said printing wheels; means to move the pawls associated with certain of said wheels out of operative relation with the wheels while the rake continues to oscillate, whereby said certain wheels remain stationary and hold a record registered thereby while the other wheels continue to be operated; means to print a record from all said wheels; and means associated with said printing means for moving said certain wheels after a predetermined number of operations of the printing means to positions of readiness for operation by said pawls to make a fresh record.
